UNITED STATES PATENT OFFICE.

FRANK F. WITKUS, OF NEWPORT, NEW HAMPSHIRE.

PRESSER WHEEL.

1,407,183.

Specification of Letters Patent. Patented Feb. 21, 1922.

Application filed April 21, 1921. Serial No. 463,223.

To all whom it may concern:

Be it known that I, FRANK F. WITKUS, a citizen of the United States, and a resident of Newport, county of Sullivan, State of New Hampshire, have invented an Improvement in Presser Wheels, of which the following is a specification.

This invention relates to improvements on a form of presser foot commonly used on certain types of reciprocating needle bar sewing machines, perforating machines and the like, which comprises a wheel mounted on an arm and arranged to press the work against an intermittently driven feed wheel.

15 Prior to my invention these presser wheels have, so far as I am aware, been provided with a bearing stud which projects from the rear side of the wheel and is journaled in the end of the arm by which the wheel is carried.

20 As a rule, the work engaging face of a wheel of this type is formed obliquely to its axis, so that the wheel inclines away from the needle bar and is usually dished or recessed on its side next the needle bar, so that its

25 face may be pressed against the work as closely as possible to the path of the needle, without interference with the needle bar, or parts carried thereby. In consequence the direction of the force with which the wheel

30 is pressed against the work, or the direction of the perpendicular line to the face of the wheel, is not only at one side of the bearing of the wheel, but it is also oblique to the axis of the wheel. The combined result causes

35 the stud to be cramped in the bearing to such an extent as to interfere seriously with the free turning of the wheel, particularly as it is pressed against the work with considerable force. Consequently the bearing must

40 be kept well lubricated, to prevent the wheel from dragging on the work. Under these conditions the bearing soon becomes worn, so that parts must be replaced, and, even when the parts are new and well lubricated,

45 the wheel often does not turn with the freedom desired. The use of a lubricant, at this point, on machines for operating on shoe uppers, is especially objectionable, for, if a drop of oil falls on white or fancy colored

50 upper leather, it is very difficult, or practically impossible to remove it.

To obviate these difficulties I have proposed to provide a ball-bearing, in lieu of the cylindrical bearing which has been generally employed, but in attempting to do this, I have encountered several difficulties. It is

impractical to vary either the form of the wheel, or the form of the arm which supports it, to a substantial extent, from those now in use, on account of the space required 60 by the needle bar and the space required, in many instances, by the portion of the work which is fed beneath the hub in which the wheel is journaled, as, for instance, portions in which lacing hooks are set, and I have 65 found that a ball bearing of no greater diameter than the maximum diameter of hub which is permissible, is impractical.

The objects of my invention are to provide a practically operative form of ball bearing, 70 for a presser wheel of the above described type, which will be so arranged as to avoid binding in the bearing by the oblique application of forces to the wheel, which has a ball race of sufficiently great diameter to operate satisfactorily, and which is so constructed that the presser wheel and bearing may be applied to the wheel-carrying arm of machines now in use without alteration 75 therein.

80 I accomplish these objects in the manner hereinafter described and as illustrated in the accompanying drawings, in which:

Fig. 1 is a side elevation of a presser wheel provided with an embodiment of my 85 invention.

Fig. 2 is a front view of the wheel on an enlarged scale.

Fig. 3 is a longitudinal sectional view at line 3—3 of Fig. 1.

90 Figs. 4, 5 and 6 are plan and sectional views of a tool which I preferably employ in assembling the bearing.

In Fig. 1 of the drawing the application of the presser wheel to a common form of 95 reciprocating needle bar sewing machine is indicated, the presser wheel *a* being shown as pressed down on the work directly above the feed wheel *b* and adjacent the needle bar *c*, by an arm *d*.

100 According to my invention, and particularly as illustrated in Figs. 2 and 3, the wheel *a* is made in the form of a ring, the work engaging face *a'* of which is oblique to the plane of the side of the ring, and tapers 105 from the front side. The front side of the ring is dished out or recessed to the depth which wheels of this character are usually recessed, so that the thickness at the inner periphery is less than half that at the outer 110 periphery. The edge, at the inner periphery, is grooved to form a ball race *a''* adapt-

ed to receive a set of bearing balls e , the side edge of the groove, which is in the plane of the rear side, being of less diameter than that at the front side. A bearing member is provided which comprises a screw threaded shaft f which extends through the ring a , having a flat circular head f' , at one end, the diameter of which is preferably slightly less than the internal diameter of the wheel aperture, and, when in position, said head will project only slightly beyond the bottom of the recess in the front side of the ring, so that it will lie well out of the path of movement of the needle bar. The edge of the head f' is beveled or slightly grooved at its rear side, to provide a circular ball-engaging face, f^2 which is disposed in opposite relation to the rear side portion of the ball race groove a^2 .

20 A sleeve g is threaded on the shaft f and is provided with a flange g' , at its end adjacent the rear side of the ring a , said flange being of approximately the same diameter as the head f' , and the edge thereof being slightly beveled, at g^2 , to provide a circular ball-engaging face in opposite relation to the front side of the groove a^2 , the beveled faces f^2 and g^2 thus being arranged in convergent relation, and, in effect, form, when in adjusted position, the opposite sides of a ball race groove which is opposed to the ball race a^2 . The arrangement is, therefore, such that the balls e will be held in position by the three bearing surfaces, a^2 , f^2 and g^2 , and the balls will hold the ring a in position with relation to the other bearing members. A roller bearing is thus provided between the members f and g and the ring. Adjustment of the bearing is effected by adjusting the sleeve g on the shaft f , so that the ring will run freely without lateral motion. The groove a^2 is arranged somewhat obliquely with relation to the plane of the side of the ring, so that a line from the center of any one of the bearing balls to the middle, transversely, of the groove a^2 will be practically perpendicular to an element of the work-engaging face a' .

Consequently, pressure applied to the face a' will be received at the middle of the groove a^2 , so that there will be no tendency to cramp the bearing, or restrain it from free action, and lubrication will be unnecessary.

The external diameter of the sleeve g is such that it will fit closely into the aperture in the end of the arm d , the arm being clamped against the flange g' by a nut h threaded on the shaft f . In some instances the diameter of the aperture of the arm d which supports the wheel is such that the shaft f , instead of the sleeve g will fit therein, and in such case the arm would be clamped against the end of the sleeve. The sleeve g may, however, be made integral with the arm d , if desired, in which case the diameter

of the hub-portion may be substantially reduced.

As the parts are difficult to assemble and adjust without the aid of special devices, I provide a holder i adapted to receive the wheel and the head of the shaft f , as shown in Fig. 6, to hold the same in the desired relation, so that balls may be placed in position and then the sleeve may be screwed down on the shaft so as to confine the balls in the ball race of the wheel, the shaft f being held from turning, as the sleeve is screwed down, by pins j' mounted in the holder and engaging the head f' in apertures formed in the end thereof.

I claim:

1. A presser wheel for the purpose described consisting of a ring having its peripheral face extending convergently from its front side and a ball race groove in its inner periphery arranged correspondingly to said face to receive the thrust thereon, a series of bearing balls in said groove, a shaft extending through said ring and having a circular head thereon at the front side of said ring, a bearing flange at the rear side of said ring, having a screw-threaded connection with said shaft, said head and said flange having circular bearing faces arranged for cooperative engagement with said bearing balls, and means for supporting said shaft at the rear side of the wheel.

2. A presser wheel for the purpose described consisting of a ring having a recessed front side and a flat rear side, and having its peripheral, work-engaging face, extending convergently from its front side and a ball race groove formed in its inner peripheral edge in position to directly receive the thrust on said work-engaging face, a series of bearing balls in said groove, a shaft extending through said ring and having a circular head thereon at the front side of said ring, a supporting arm and a bearing flange carried by said arm at the rear side of said ring and having a screw-threaded connection with said shaft, said head and said flange having oppositely disposed, circular faces arranged for cooperative engagement with said bearing balls.

3. A presser wheel for the purpose described consisting of a ring having an outer peripheral, work-engaging face and an inner peripheral ball-race groove, a series of bearing balls in said groove, a screw-threaded shaft extending through said ring and having a disk-like head at its front end disposed between the front side of said ring and the plane of the front edge of its face, said head having a circular face arranged to engage said bearing balls oppositely to the rear side of said groove, and a sleeve screwed on said shaft having a circular bearing flange at its end adjacent the rear side of the ring, and said flange having a circu-

lar face arranged to engage said balls oppositely to the front side of said groove.

4. A presser wheel for the purpose described consisting of a ring recessed from its front side and having an outer peripheral work-engaging face extending obliquely toward its axis from the front side, the inner peripheral surface of said ring being formed between the bottom of the recess and its rear side and having a ball race groove so formed therein that its rear edge is of a less diameter than its front edge, a shaft extending through said ring and having a head at its front end, said head having a ball race 10 obliquely arranged to engage said balls oppositely to the rear side of said groove, and a sleeve threaded on said shaft and having a circular flange providing a bearing surface arranged to engage the balls oppositely 15 to the front side of said groove.

5. A presser wheel for the purpose described consisting of a ring having an outer peripheral work engaging face, with its front side recessed from the front edge 20 of said face, and having an inner peripheral ball - race groove, a series of bearing balls in said groove, a shaft extending through said ring having a disk-like head at its front end arranged within said recess and

having a ball-race in opposite relation to the rear side of said groove, a bearing member on said shaft arranged for adjustment relatively to said head and having a ball race in opposite relation to the front side of said groove and cooperating with said head to support the balls therein, and supporting means for said shaft at the rear side of said ring. 30 35

6. A presser wheel for the purpose described consisting of a ring having an outer peripheral work-engaging face, with its front side recessed from the front edge of said face and having an inner peripheral ball-race groove so arranged that its rear edge is of less diameter than its front edge, a series of bearing balls in said groove, a shaft extending through said ring and having a disk-like head thereon at the bottom of said recess, said head having a ball-race arranged to face the rear side of said groove, a bearing member adjustably mounted on said shaft and having a ball-race arranged in convergent relation with that of said head, to support the balls in position in said groove, and supporting means for said shaft at the rear side of said ring. 40 45 50 55

In testimony whereof, I have signed my name to this specification.

FRANK F. WITKUS.
